BAFFLE MEMBER FOR COMBUSTION CHAMBERS

William R. Howland, Milton Junction, and Ivan D. Teft, Janesville, Wis., assignors to Vape-O-Plate Co., Janesville, Wis., a corporation of Wisconsin

Application August 14, 1950, Serial No. 179,342

3 Claims. (Cl. 110—97)

This invention relates to combustion aids for heating units.

The principal object of this invention is to provide a highly efficient baffle for easy installation over and adapted to function in conjunction with the combustion chamber of a heating unit; which baffle is constructed of a high diffusivity metal, and is so shaped and so positioned relative to said combustion chamber as to greatly increase the combustion efficiency of said heating unit, and thus reduce fuel costs.

Another object of this invention is to provide a combustion aid for heating units which not only serves as a combustion aid, but also serves as a heat diverter, as it is so formed and positioned over the combustion chamber as to divert the heat of the flame from a substantially vertical and central path in the furnace, to a path closely following the contour of the heat-transfer wall over the entire height of said wall, thus causing the heat to impinge on the heat-transfer wall in such manner as to utilize said entire wall as a radiator, and increasing the thermal efficiency of said furnace by transferring more of the heat of the flames to the medium to be heated.

Yet another object of this invention is to provide a combustion aid for heating units which has adjustable legs as to enable the installer to properly position said combustion aid on combustion chambers of a relatively wide range of diameters.

A further object of this invention is to provide a combustion aid which improves the operation of heating units by slowing down the speed of the hot products of combustion in their path through the furnace, and by increasing the turbulence in the combustion chamber to aid the completion of combustion, thus reducing the amount of unburned or partially burned fuel and the unpleasant odor of such, and to aid in quieting and muffing of the flame roar.

Yet a further object of this invention is to provide a combustion aid for intermittently-fired furnaces such as oil burning furnaces, which while inexpensive to produce, is sturdy and will not crack and disintegrate as do refractory plates, when subjected to the repeated stresses set up by alternate heating and cooling.

Other objects and advantages of this invention will become apparent from a description of a preferred embodiment of the invention taken in connection with the appended drawings, in which:

Figure 1 is a perspective view of a coal furnace converted to the use of oil with the combustion aid installed; the furnace casing, firepot, ashpit, 55

and cement fill being cut away to expose said combustion aid and the refractory combustion chamber.

Fig. 2 is an enlarged, fragmentary perspective view of the firepot, ashpit, and cement fill, which have been cut away to disclose the combustion aid and the combustion chamber.

Fig. 3 is an enlarged, fragmentary sectional view taken through the center of the firepot, ashpit, combustion chamber, and combustion aid.

In Fig. 1 the combustion aid 10 is shown positioned in a cast iron type coal furnace which has been converted to the use of oil. The unit disclosed comprises a casing 11 and a bonnet 12, both enclosing a radiator 13, a furnace proper 14, a firepot 15, an ashpit 16, and an ash clean-out bay 17 assembled in conventional manner. Conversion of said heating unit to the use of oil has been accomplished by the removal of a coal grate formerly situated at the bottom of the firepot 15, and the construction in the ashpit 16 of a combustion chamber 18 with refractory walls 19 and refractory floor 20, with cement fill 21 poured between the wall of said ashpit 16 and walls 19. A standard gun type oil burning conversion unit 22 having a nozzle 23 is shown installed adjacent the heating unit, with said nozzle projecting slightly into the combustion chamber 18. Our combustion aid 10 is shown properly positioned relative to the combustion chamber 18, said positioning being accomplished by proper adjustment of the height and straddle-diameter of the supporting legs.

The combustion aid 10 comprises a disc-shaped body 24 of sheet stainless steel spun or stamped into a substantially frusto-conical shape with a plurality of concentric annular lands 25 spaced along the angular walls of said body, which lands serve to increase the radiating area of said body, and to slow down and impart turbulence to the burning air-fuel mixture when the burner is in operation.

The body 24 is fashioned of sheet stainless steel, which will not crack, check, or disintegrate as refractory plates do. Said body is of high thermal conductivity, and thus will heat up extremely rapidly. This is an important consideration in the operation of an intermittently-fired furnace, where a large drop in the combustion efficiency is caused by the lag between the time that said furnace "goes on" to burn fuel, and the time that the refractory materials in the combustion chamber heat up to aid such combustion.

The central portion 27 of the body 24 is dished

and provided with perforations 28 to prevent the formation of a heat pocket under said body, to reduce the possibility of burning out said central portion, and to provide additional air circulation paths to aid combustion.

The supporting legs 26 are preferably three in number so as to provide stable support for the body 24, and are disposed in an evenly-spaced arrangement about the circumference of said body. Each of said legs comprises an angled member having a horizontal portion 29 adapted to engage in apertures stamped in the annular walls of the body 24. Thus the legs 26 can be slid radially centerward and outward of the body 24, permitting one size of combustion aid 10 to be positioned on combustion chambers of a wide range of diameters.

The outermost land 25a of the body 24 is perforated at 30 for each of the legs 26 by a perforating die so constructed as to form an aperture 30 and form a strap 31 projecting outward from said outermost land. The horizontal portions 29 of the legs 26 slidably pass through said straps 31, and pass into the frusto-conical interior of the body 24 through rectangular perforations 32 established inwardly of said straps in said body.

Each of the legs 26 has a plurality of horizontal, deeply-scribed lines 33, which permit the easy shortening of said legs by merely knocking or bending off the length of leg desired to be removed. Thus the combustion aid 10 can be easily positioned on any size or shape of combustion chamber.

We claim:

1. A heating unit comprising an upright, generally cylindrical wall having at least its inner face portion formed of a refractory material and defining a combustion chamber having an open upper end, a fuel burner for delivering fuel into said chamber and burning it therein, and a combustion aid device including a hollow, generally conical baffle member formed from stainless steel and of substantially uniform thickness and having formed therein a plurality of concentric, annular lands with their faces generally perpendicular to the axis of said baffle member, and a plurality of legs spaced circumferentially around and extending radially from said baffle member, each leg having a downturned end resting upon the top edge of said wall, said legs together supporting said baffle member apex-downwardly in a position generally in alignment with said combustion chamber and spaced from but sufficiently close to the top edge of said wall to define an

annular outlet from said combustion chamber and whereby substantially all of the heat which is reflected by the lower face of said baffle member is reflected into said chamber.

2. A combustion aid device adapted for installation over a combustion chamber of the type defined by an upright wall and having an open upper end, said device comprising a hollow, generally conical baffle formed from stainless steel of substantially uniform thickness, a plurality of circumferentially spaced supporting legs extending radially from said baffle member, each leg having a generally horizontal portion connected to said baffle member and a downturned outer end portion outwardly beyond said baffle member for supporting said device on the top edge of the combustion chamber wall, and means formed on said baffle member intermediate the apex and base edge and slidably receiving the horizontal portions of said legs respectively connecting said legs to said baffle member for radial adjustment relatively to the latter.

3. A combustion aid device adapted for installation over a combustion chamber of the type defined by an upright wall and having an open upper end, said device comprising a hollow, generally conical baffle member formed from stainless steel and having formed therein a series of concentric annular lands with their faces generally perpendicular to the axis of said baffle member and a plurality of circumferentially spaced, depending straps and corresponding perforations radially inwardly of said straps respectively, and a plurality of supporting legs each having a generally horizontal portion extending through one of said straps and the corresponding perforation and frictionally but slidably held thereby for adjustably supporting said device on the top edge of the combustion chamber wall.

WILLIAM R. HOWLAND.
IVAN D. TEFFT.
